(74) Attorney, Agent, or Firm — Peter L. Holmes, Esq.

(57) **CLAIM**

The ornamental design for a skateboard with dragon-shaped features, as shown and described.

DESCRIPTION

FIG. 1 is a top front perspective view of a skateboard showing my new design;

FIG. 2 is a right side elevation view thereof;

FIG. 3 is a left side elevation view thereof;

FIG. 4 is a rear side elevation view thereof;

FIG. 5 is a front side elevation view thereof;

FIG. 6 is a top plan view thereof; and,

FIG. 7 is a bottom view thereof.

The broken lines are included for purposes of illustrating portions of the skateboard article embodying the design and form no part of the claimed design.

1 Claim, 6 Drawing Sheets

FIG. 2

FIG. 3

FIG. 5

FIG. 4

FIG. 6

FIG. 7
